FIELD GATE

FILED JULY 22, 1922.

3 SHEETS—SHEET 3.

UNITED STATES PATENT OFFICE.

WILLIAM G. STADERMANN, OF ELERoy, ILLINOIS.

FIELD GATE.

Application filed July 22, 1922. Serial No. 576,720.

To all whom it may concern:

Be it known that I, WILLIAM G. STADERMANN, a citizen of the United States, residing at Eleroy, in the county of Stephenson 5 and State of Illinois, have invented a new and useful Field Gate, of which the following is a specification.

This invention relates to swinging gates, and more particularly swinging gates operating in horizontal planes.

The primary object of the invention is to provide a novel form of operating means, whereby the gate may be moved to its open or closed position, from a point remote from 15 the supporting posts thereof, thereby eliminating the necessity of a person alighting from his vehicle to operate the gate.

Another object of the invention is to provide a gate of this character which will automatically lock when moved to its closed position, and one wherein the locking means 20 will be automatically operated when the gate operating means is moved.

A still further object of the invention is to 25 provide pulleys, chains moving over the pulleys and operating levers for moving the chains, novel means being provided for automatically throwing the pulleys into and out of operation, when the levers are moved.

With the foregoing and other objects in view which will appear as the description proceeds, the invention resides in the combination and arrangement of parts and in the details of construction hereinafter described 35 and claimed, it being understood that changes in the precise embodiment of the invention herein disclosed, may be made within the scope of what is claimed, without departing from the spirit of the invention.

Referring to the drawings:—

Figure 1 is an elevational view of a gate and operating mechanism constructed in accordance with the invention.

Figure 2 is a plan view thereof.

Figure 3 is a sectional view taken on line 3—3 of Figure 1.

Figure 4 is a sectional view taken on line 4—4 of Figure 1.

Figure 5 is an enlarged detail view 50 closing the pinion and spring operating means for controlling the movements of the gate.

Figure 6 is an enlarged sectional view 55 showing the manner of supporting the pulleys.

Figure 7 is a sectional view taken on line 7—7 of Figure 1.

Referring to the drawings in detail, the reference character 5 designates supporting posts, which are disposed in spaced relation 60 with each other as clearly shown by Figure 1 of the drawings. Secured to the post 5 are the upwardly extended supporting bars 6, which have their upper ends curved laterally where they support the shaft 7 that extends through suitable openings formed adjacent to the upper ends thereof.

Mounted on one end of the shaft 7, is a beveled pinion 8 that meshes with the beveled pinion 9 loosely mounted at the upper end 70 of the end member 10 of the gate, so that movement of the shaft 7 and pinion 8, will result in a relative rotary movement of the pinion 9.

Secured to the pinion 9 is an arm 11 that 75 has pivotal connection with the rod 12 as at 13, the outer end of the rod 12 supporting the coiled spring 14 which is held on the rod by means of the nut 15. This rod 12 operates through the bearing 16 and provides a 80 stop for one end of the coiled spring 14, so that when the rod 12 is moved in one direction, the spring 14 is placed under tension to accomplish the movement of the gate proper when the latch mechanism has been 85 operated.

The latch mechanism embodies a housing 17 secured to the outer end of the gate proper, which housing is formed with openings to accommodate the sliding bolts 18 and also 90 pass through openings in the end member 19, of the gate, the free ends of the bolts 18 being designed to move within openings provided in the keeper 20. Coiled springs 21 are supported on the sliding bolts 18 and 95 are placed under tension when the sliding bolts are moved to positions to unlatch the gate so that the coiled springs will normally urge the sliding bolts to the limits of their outer positions.

A pivoted arm 22 is supported by the gate and has its lower end terminating at a point in proximity to the sliding bolts, where the same is connected to the sliding bolts as by means of the connecting rods 23. A rod 24 105 is connected with the pivoted arm 22 and has its upper extremity connected with the chains 25 that have connection with the beveled pinion 9 at points adjacent to the periphery thereof, so that movement of the pinion 9, 110

will produce a relative movement of the chains 25.

Secured to the shaft 7 is a clutch member 26 which is formed with clutch faces 27 and 28 respectively, which clutch faces are designed to cooperate with the clutch faces 29 formed on the pulleys 30 and 31 respectively. These pulleys 30 and 31 are loosely mounted on the shaft 7 and are normally urged towards the clutch member 26 as by means of the coiled springs 32 and 33 respectively.

Extending above the shaft 7 and supported by the posts 5 is a frame 34 that has an upper bar 35 to which the brackets 36 are secured, the brackets providing supports for the pivot pins 37 that pass through the operating arms 38 and 39 respectively. As shown these arms extend inwardly, and are of lengths to overlie the central portion of a road closed by the gate, to permit an operator to readily grasp the arms to accomplish the operation thereof.

Each of the pulleys is divided as by means of a circular partitioning member 40, thereby providing a pair of chain engaging surfaces on each pulley. A chain 41 is connected to one end of the arm 38 and has a portion thereof wound on one of the pulleys, the opposite end of the chain being secured to the pulley so that when the arm 38 is moved, the pulley will be rotated in one direction. A chain 42 has one end secured to the pulley associated therewith and has its opposite end connected to the coiled spring 43 that is secured to the upper bar of the frame 34.

A chain 44 has one end thereof secured to the arm 39, the opposite end thereof being secured to the pulley associated therewith, while the chain 45 which is also secured to the pulley associated therewith, has one end secured to the spring member 46. Pivotally connected to each of the arms is a clutch arm 47 which is formed with an elongated opening to accommodate the shaft 7 and permit the clutch arm to move at right angles with respect thereto. At the lower end of each of these clutch arms are inwardly extended camming flanges 48, which flanges lie between the clutch member 26 and pulleys supported on the shaft 7. Thus it will be seen that as the arms 38 and 39 are moved down-

wardly, the camming flanges are moved out of contact with the clutch member 26 permitting the coiled spring associated therewith to force the clutch face of the pulley into engagement with the clutch face of the clutch member 26, that lies adjacent to the pulley being operated to lock the pulley to the shaft 7 and cause rotation of the shaft.

As the shaft 7 rotates the pinion 8 also rotates, which in turn transmits rotary motion to the pinion 9 in a manner as heretofore described.

It is believed that in view of the foregoing, a further detailed description of the device is unnecessary.

Having thus described the invention, what is claimed as new is:

1. In combination with a swinging gate, an operating mechanism including, a horizontal shaft, pulleys loosely mounted on shaft, a clutch member secured to the shaft, said clutch member having clutch faces, pulleys loosely mounted on the shaft and having clutch faces, clutch arms, operating arms supporting the clutch arms, said clutch arms adapted to move between the pulleys and clutch member to normally hold the pulleys out of engagement with the clutch member, said clutch arms adapted to move to clutch the pulleys to the shaft, and means for transmitting rotary movement of the shaft to the gate.

2. In combination with a swinging gate, an operating mechanism including a shaft, pulleys loosely mounted on the shaft, a clutch member on the shaft carrying clutch faces, pulleys loosely mounted on the shaft and having clutch faces, spring members on the shaft for normally urging the pulleys to the clutch members, operating arms for operating the pulleys, means carried by the operating arms and movable between the pulleys and clutch member for urging the clutch faces out of engagement, and means for transmitting movement of the shaft to the gate.

In testimony that I claim the foregoing as my own, I have hereto affixed my signature in the presence of two witnesses.

WILLIAM G. STADERMANN.

Witnesses:

M. D. SHEETZ,

Wm. HANKE.
